GARBAGE CAN HOLDER

Marion Young, 1624 W. 23rd, Little Rock, Ark.

Filed Oct. 30, 1961, Ser. No. 67,296

Term of patent 7 years

(Cl. D58—26)

FIG. 1

I claim:

The ornamental design for a garbage can holder, as shown.
